UNITED STATES PATENT OFFICE.

GEORGE S. HENRITZY, OF HAZLETON, PENNSYLVANIA.

AWNINGS.

Application filed June 27, 1922. Serial No. 571,193.

This invention relates to awnings and particularly to those awnings which may be readily rendered so that they do not obstruct the light at the window or door when not in use.

The primary object of my invention is the provision of an improved awning that may be folded and rolled so as to offer absolutely no obstruction to the light entering the door or window where the awning is installed.

Another object of my invention is the provision of an awning which may be folded and entirely rolled on a roller and yet when in operative position may have a lower edge 15 which lies substantially in a horizontal plane.

Referring to the drawing where a preferred embodiment of my invention is illustrated,

Fig. 1 is a perspective view showing the awning in operative position and at the middle of the window.

Fig. 2 is a perspective view showing the awning in operative position and pulled down to shade the whole window.

Fig. 3 is a perspective view showing the awning folded and indicating the folded portions in dotted lines.

Fig. 4 is a perspective view of the awning folded and rolled.

Fig. 5 is a perspective view of the end of the frame member 16.

Fig. 6 is a perspective view of the securing means for the lower portion of the awning.

In the drawings, 10 designates the window frame upon which the awning is shown mounted. Brackets are provided for supporting the spring awning roller 11. Attached to the awning roller is the part 12 of the awning which is a flat piece of the flexible awning material. This part of the awning rolls on the roller without being folded and when in extended position always lies substantially in or near the plane of the window frame. Secured to the lower edge of the upper portion 12 of the awning is the extended portion formed by the two triangular portions 13 and 14 and the rectangular portion 15. At the lower edge of these three portions 13, 14 and 15 is a three part frame 40 comprised of the parts 16, 17 and 18. The part 16 is adjacent the bottom of the triangular portion 13 and preferably within a fold thereof. The part 17 is arranged adjacent the bottom of the portion 15 and preferably within a fold thereof. The portion 18 is arranged adjacent the triangular portion

14 of the awning and preferably within a fold thereof. The portions of the frame 16 and 18 are hingedly connected at respective ends of the frame member 17. These hinges 60 are of the rule joint type and preferably have a normal angular opening of slightly less than 90° so that when the side frame members 16, 18 are opened wide, the hinges will be stiff and resist the wind thereby holding the awning tight and preventing rattling. Secured to the window frame at each side is a catch or securing means having a body portion 19 with screw holes provided for attaching the same to the window frame. 70 A hook member 20 extends from the body portion 19 and a locking member 21 is suspended thereabove to prevent accidental disengagement of the eye 22 one of which is located on the inner end of each of the frame 75 members 16 and 18. Several pairs of these fastening means 20 may be used making the awning available at different heights, as can be readily seen by a comparison of Figures 1 and 2.

Below the frame 16, 17, 18 and attached to the awning parts 13, 15 and 14 is a strip of the flexible material of which the awning is made. This strip comprises the portions 23, 24 and 25 which are so shaped that they 85 hang in substantially a vertical plane and their bottoms lie substantially in a horizontal plane.

In order to hold the awning positively in its lower position, I have provided a cord 26 90 which is secured to the frame member 17 as at 27. This cord 26 has been provided with an eye 28 at a distance from its fastening point 27 equal to twice the width of the part 24 of the awning for a purpose to be described.

Secured at one side to the frame member 16, is a hook member 29. Secured also to the frame member 17 and extending outside of the awning part 24 is a hook 30. The hook 30 is preferably placed at a point midway between the hinges and the hook 29 is placed at the same distance from the adjacent hinge.

When it is desired to fold and roll the awning, the locking members 21 are moved to one side and the eyes 22 on the end of the frame members 16 and 18 are lifted from over the hooks 20. The hinged frame members 16, 18 are now folded inward adjacent the frame member 17, the frame member 18 being preferably folded first. As these

frame members are folded inward, the lower portions 23, 24 and 25 are folded up, the eye 28 being at this time attached to the hook 30. When the frame member 18 has been 5 folded between the frame member 17 and the frame member 16, then the cord 26 is looped over the hook 29. The awning is then lying flat with its whole frame portion lying at the bottom.

10 The spring roller is preferably of the common shade roller type. With the parts arranged as just described, it is only necessary to pull the cord to release the dogs of the spring roller and permit the spring to 15 raise and roll the awning in a manner similar to the rolling of the common window shade.

Figure 4 illustrates the awning when fully rolled.

20 It is to be noted that while the awning when spread resembles very much the awning most commonly found on buildings; when rolled up, it is entirely away from the window and cannot rattle when the wind blows.

25 In the first installation of this awning, it is only necessary to place the four screws for the roller brackets and two for each of the securing means for the lower end of the awning. In putting the awning up in the spring and taking it down in the fall, no greater amount of labor is required than putting up or taking down a shade.

30 While I have described an embodiment of my invention, I desire to have it understood that I do not limit myself to the exact form

shown and that modifications and changes may be made without departing from the spirit of my invention and within the scope of the appended claim.

Having described my invention, what I claim is:—

An awning comprising a roller, a flexible body member having its upper edge attached to the roller and having a front and side portions, a hinged three part frame for shaping the flexible body member adjacent its bottom, the middle section of the hinged frame being secured across the same and of a length to hold smooth that part of the front portion 45 between itself and the roller, the side portions of the frame being secured to the side portions of the flexible body member, the two being foldable in a flat position against the front member with the two side frame 50 members lying along the front frame member, the flexible body member being provided with a substantially rectangular portion below the front frame member and with portions below the side frame members, attached to the rectangular portions at their 55 respective front ends, to the side portions at their respective tops and tapering from front to rear, the portions below the frame being foldable above the frame and within 60 the front and sides of the body member whereby the whole body member when so folded may be rolled upon the roller.

In testimony whereof I hereunto affix my signature.

GEORGE S. HENRITZY
